UNITED STATES PATENT OFFICE.

ALBERT J. BAUM, OF NEW YORK, N. Y., ASSIGNOR TO ALBERT WANNER, JR., OF NEW YORK, N. Y.

DESIGN FOR A CHAIR.

48,851.

Specification for Design.

Patented Apr. 11, 1916.

Application filed December 20, 1915. Serial No. 67,918. Term of patent 14 years.

To all whom it may concern:

Be it known that I, ALBERT J. BAUM, a citizen of the United States, residing in the borough of Manhattan, city and State of New York, have invented a new, original, and ornamental Design for a Chair, of which the following is a specification, reference being had to the accompanying drawing, forming a part thereof.

The figure is a perspective view of the chair showing my new design.

I claim:

The ornamental design for a chair, substantially as shown.

ALBERT J. BAUM.
